UNITED STATES PATENT OFFICE.

ROBERT BIDDLE, JR., AND EDWARD J. FROST, OF PHILADELPHIA,
PENNSYLVANIA.

HYDROCARBON INCANDESCENT BURNER.

SPECIFICATION forming part of Letters Patent No. 609,653, dated August 23, 1898.

Application filed March 8, 1898. Serial No. 673,090. (No model.)

To all whom it may concern:

Be it known that we, ROBERT BIDDLE, Jr., and EDWARD J. FROST, of the city of Philadelphia, State of Pennsylvania, have invented 55
5 certain new and useful Improvements in Hydrocarbon Incandescent Burners, of which the following is a full, clear, and exact description, reference being had to the accompanying drawings, forming part of this specification.

10 Our invention has reference to hydrocarbon-burners; and it consists in the improved construction of burner hereinafter particularly described and claimed.

15 Our present invention has particular reference to incandescent burners adapted for use especially of hydrocarbon oils of low gravity.

20 In burners of the hydrocarbon class heretofore invented great difficulty has been experienced in producing the desired results when low-gravity oil has been used in operating them.

25 The object of our present invention is to provide a construction of burner wherein the best results may be obtained from the hydrocarbon oil, especially of low gravity, and to obtain from their use the highest possible efficiency.

30 A further object of our invention is to secure the greatest efficiency in a hydrocarbon-burner of the simplest construction, having the parts reduced to a minimum, preventing the liability of getting out of order and reducing the cost of construction.

35 We are aware that hydrocarbon-burners of the incandescent class have been invented of various constructions, all of which vary one from the other in detail of construction and most of which involve, essentially, the same principle of operation.

40 In burners of the hydrocarbon type in order to produce the best result it is essential that a mixing-chamber of considerable area between the point of admission of the air and gas and the burner proper be provided, and in providing for this feature it has been customary in most of the constructions of burner to set the injector in the base of the burner-frame at a considerable distance from the point of combustion. It is also essential in order to produce the best results, espe-

cially in burners wherein oils of low gravity are to be used, that the injector shall be subjected at all times while the lamp is burning to a high degree of heat. It is the aim of our 55 invention to provide an improved construction of hydrocarbon incandescent burner embodying these essential features, as herein-after particularly described and claimed.

60 In the accompanying drawings, Figure 1 is a sectional elevation of an incandescent hydrocarbon-burner embodying our invention. Fig. 2 is a sectional elevation of another form of burner embodying our invention, slightly modified from that shown in Fig. 1. Fig. 3 65 is a cross-sectional view on the line *x x* of Fig. 1.

As herein illustrated, we provide an inverted injector *a* in the main casting or body portion *A* in close proximity to and preferably 70 integral with the upper cylindrical burner portion proper, *b*, which becomes highly heated in the operation of the lamp, and consequently transmits the heat directly to and maintains that portion of the casting *A* containing the 75 injector in a highly-heated state at all times while the lamp is burning. The inverted injector *a* is connected with the cylindrical burner-casing *b* by the elongated mixing-chamber *C C'*, preferably U-shaped. The 80 air-intake *d*, located between the injector-point and the upper end of the chamber *C*, is preferably incased in a gauze covering *c*. The upper end of the section *C'* of the mixing-chamber communicates directly with and 85 opens into the chamber *b'*, formed by the cylindrical walls of the burner-section *b*. The direction of the flow of fluids is indicated by the arrows.

90 In the construction shown in Fig. 1 the section *e* of the main casting *A*, of narrow width, contains the horizontally-disposed oil and gas channels *f' f''*, hereinafter described, and intersects the mouth of the mixing-chamber *C'* at the point of connection with the chamber 95 *b'*, though sufficient area is left around the same for the free and unobstructed passage of the mixed air and gas to the burner, as indicated in Fig. 3.

100 In our hydrocarbon-burner described we preferably employ the construction of vertically-disposed elongated vaporizer which we

have described and claimed in our application for Letters Patent filed of even date herewith, consisting, essentially, of the small elongated oil-supply tube b^2 and the return gas-tube b^3 , the oil-tube b^2 being connected with the oil-supply pipe f through the medium of the channel f' , and the tube b^3 discharges into the gas-channel f^2 , connecting with the injector a .

10 In the construction shown in Fig. 1 the return gas-tube b^3 is located within the vaporizing-tube b^2 , of larger diameter, while in the construction shown in Fig. 2 the vaporizing-tube b^2 and gas-tube b^3 are formed in one continuous elongated U-shaped tube.

15 The tubes b^2 b^3 are provided vertically and centrally within the mantle g , which is secured upon the burner, as by the supporting-rod h or by any suitable means, and being thus centrally located within the said mantle throughout nearly its entire length is subject to the greatest heat produced by the mantle focusing toward its longitudinal center, thus accomplishing and insuring complete vaporization.

20 The usual supply-valve i is provided in the pipe f and screw-threaded pin-valve j in the channel f^2 to regulate the flow of gas and oil, respectively. To provide ready means of access to the injector-channel, we preferably continue the said channel through the walls of the casing and close the same by a screw-threaded plug k .

25 In operation the lamp is started, as usual in hydrocarbon-lamps such as have no fixed auxiliary heater, by holding an ordinary heating-lamp in proximity with the upper portion of the burner, which when heated vaporizes a small quantity of oil and produces a small amount of gas sufficient to ignite above the burner and start the lamp. The mantle thus becoming partially incandescent the heat therefrom commences to generate more gas in the vaporizing-tube as the oil flows, properly regulated, from the pipe f to the channel f' into the vaporizing-tube b^2 . The gas thus generated passes into and through the tube b^3 and through the channel f^2 to the inverted injector a . At this point the air passing into the port d mixes with the gas in the elongated mixing-chamber, comprising the U-shaped sections C c' , and from thence in a properly commixed and commingled condition the gas and air pass to and out of the burner-section b , where combustion takes place upon the walls of the mantle g .

It will be clear from the construction described of inverted injector located in close proximity to the heated cylindrical burner-section b that an intense heat is constantly maintained in the injector-section and that from that point to the point of combustion an area of mixing-chamber is provided to any desired extent. It is also clear that in our construction of lamp above described hydrocarbon oils even of the lowest gravity may be most satisfactorily employed in operating the lamp.

Having thus described our invention, what we claim, and desire to secure by Letters Pat- 70 ent, is—

1. In an incandescent hydrocarbon-burner a burner-section having a chamber therein, a main body portion, a tubular vaporizer and a return gas-tube provided vertically and centrally within a mantle, an inverted injector provided in the main body portion substantially centrally in the length of the combined burner, an air-inlet port and a depending enlarged mixing-chamber connecting the said inverted injector and the air-inlet port with the chamber in the burner-section, substantially as described. 75

2. In an incandescent hydrocarbon-burner, a main body portion, a burner-section provided thereon, a tubular vaporizer and return gas-tube provided vertically and centrally within the mantle, an inverted injector provided in the main body portion near the burner-section, an air-inlet port and a depending mixing-chamber connecting the said inverted injector and air-inlet port with the burner-section, substantially as described. 80

3. In an incandescent hydrocarbon-burner, a main body portion, a cylindrical burner-section provided thereon, a mantle, an elongated tubular vaporizer and return gas-tube provided vertically and centrally within the mantle, an inverted injector provided in the main body portion substantially centrally in the length of the combined burner, an air-inlet port, and a depending U-shaped mixing-chamber connecting the said inverted injector and air-inlet port with a chamber in the burner-section, substantially as described. 90 100 105

In witness whereof we have hereunto set our hands this 7th day of March, A. D. 1898.

ROBERT BIDDLE, JR.
EDWARD J. FROST.
